Patented Sept. 13, 1921.
2 SHEETS—SHEET 2.

UNITED STATES PATENT OFFICE.

ANTHONY PETER DOELL, OF MINNEAPOLIS, MINNESOTA.

DRAFT-PRODUCING DEVICE.

1,390,889.

Specification of Letters Patent. Patented Sept. 13, 1921.

Application filed June 7, 1920. Serial No. 387,259.

To all whom it may concern:

Be it known that I, ANTHONY PETER DOELL, a citizen of the United States, residing at Minneapolis, in the county of Hennepin and State of Minnesota, have invented a new and useful Draft-Producing Device, of which the following is a specification.

My invention relates to improvements in draft producing devices.

10 Its object is to provide a simple and durable device for accelerating the draft in a chimney.

15 A further object is to provide a knock-down device of this kind designed to be readily passed through a pipe-hole in a chimney and quickly and easily assembled therein.

20 A further object is to provide a heat radiating attachment for flues, together with a pan designed to be placed, therebeneath, said pan providing a self-cleaning false bottom in the flue and also serving to direct heated gases, against the members of said radiating attachment, upon their entry into the flue.

25 With the foregoing and other objects in view, which will appear in the following description, the invention resides in the novel combination and arrangement of parts and in the details of construction hereinafter described and claimed.

30 In the drawings, Figure 1 is a fragmentary perspective view of a flue or chimney containing a device embodying my invention; Fig. 2 is a plan view in detail of the hanger; Fig. 3 is a perspective view in detail showing one of the radiating plates; Fig. 4 is an elevation in detail of the clip and Fig. 5 is a perspective view showing, in detail, the members of the deflecting pan.

40 Referring to the drawings, it will be seen that my improved device comprises a hanger A, radiating plates B, a connecting clip C for said plates and a deflecting pan D, said parts being designed to be inserted in a pipe-

45 opening in a flue and assembled therein. The hanger A comprises two crossed metallic bars 10 pivotally connected at their intersection. The tips 11 of said bars are pointed or otherwise reduced so as to be

50 readily shaped to fit and engage the walls of a flue. These bars are formed with perforations 12 in each branch thereof for purposes as will hereinafter appear. The radiating plates B are formed of metal or other material adapted to readily conduct and radiate heat. Each plate is formed with per-

forations 13 in the upper margin thereof, through which a wire 14 may be threaded, as shown. A perforation 15 is also formed in the lower margin of each plate. The clip 60 C includes a metallic disk-like body portion 16 with a plurality of radial yielding jaws 17 thereon. Said jaws are designed to receive and grip the lower margins of the plates B and rigidly secure the same. Openings 18 are formed in said jaws to receive locking pins 19, which are passed through two or more of the jaws 17 and through the perforations 15 in the plates B. The pan D comprises two curved sheet metal members 70 20 and 21. Each member has a marginal bead 22 containing a reinforcing wire 23 extending beyond either end thereof. End portions 24 of the member 20 are turned upon the body thereof to form slides 25 for 75 the ends of the companion section.

In assembling my device within a flue, the members of the pan D are telescoped so as to pass through a pipe-opening therein. Said members are extended within the flue 80 and the pan hung therein as shown in Fig. 1. I prefer to increase the curvature of the pan, by force, within the flue so that the resiliency thereof will operate to firmly engage the projecting ends of the rods 23 with 85 the walls of the flue. It will be noted that said ends of said rods in addition to supporting the pan D, act as spacers and form openings 26 (Fig. 1) between the ends of said pan and adjacent walls of the flue. The 90 folded hanger A is inserted through the pipe-opening in the flue and thereafter opened, the ends thereof being caught in the corners of the flue. A plate B, with a wire 14 threaded therein, is passed through the 95 pipe-opening, the ends of said wires being inserted in perforations 12 in a hanger arm and bent at their tips to secure the plate to said arm. The remaining plates are similarly suspended from the remaining arms of 100 the hanger A and the clip C is thereafter affixed to said plates as described.

The pan D substantially cuts off the usual clean-out well beneath the pipe-opening, yet permits the escape of cinders and the like 105 thereto, the same being cleanly swept from the curved surface of the pan by the incoming gases from a stove or other device. The plates B divide a section of the flue into segmental compartments. This construction, 110 together with the deflecting and distributing pan D provides for applying the maxi-

mum heat to said plates and further provides for unimpaired drafts in a number of pipes entering the flue on the same level. Heat radiating from the constantly heated plates B increases the draft in a flue to a marked degree. The draft producing action of the plates B is enhanced by the pan, which, in addition to its heat distributing function, eliminates the drag usually caused by heavy, moist air in the base of a flue.

My device is simple, inexpensive, easily applied and very effective in accelerating the draft within a flue. It provides for the attainment of increased drafts, at small expense and without damage to or alteration of a flue or chimney.

Changes in the specific form of my invention, as herein disclosed, may be made within the scope of what is claimed without departing from the spirit of my invention.

Having described my invention what I claim as new and desire to protect by Letters Patent is:

1. A device of the class described, comprising the following parts, each being capable of being passed through a pipe-opening in a flue: a folding hanger designed to be supported by engagement with the walls of the flue, heat radiating plates adapted to be carried by said hanger and a pan including telescopically connected members, said pan being designed to be hung in the flue beneath said plates and direct heated gases thereagainst.

2. In a device of the class described, a hanger comprising crossed members, the ends thereof being designed to engage the walls of a flue, heat radiating plates adapted to be suspended from said hanger, opposite the pipe-opening in the flue, and arranged to divide a section of the flue into segmental compartments and a pan designed to be hung in the flue beneath said plates, said pan being adapted to direct heated gases

into all of said compartments and formed to provide an opening into the clean-out chamber of the flue for the escape of cinders or the like.

3. A device of the class described, comprising the following parts, each capable of being passed through a pipe-opening in a flue: a folding hanger designed to be supported by engagement with the walls of the flue, heat radiating plates adapted to be suspended from said hanger, opposite said pipe-opening, a clip to join said plates at the lower edges thereof and a pan including telescopically connected members, said pan being designed to be hung beneath said plates and direct heated gases thereagainst.

4. In a device of the class described a hanger comprising crossed members, the ends thereof being designed to engage the walls of a flue, a heat retaining element adapted to be carried by said hanger, opposite a pipe-opening therein, and arranged to divide a section of the flue into compartments and a heat distributing pan designed to be hung in the flue beneath said heat retaining element.

5. In a device of the class described the combination with a flue of a hanger designed to rest in the flue, radiating devices carried by said hanger in position to contact with heated gases entering the flue through a pipe-opening therein and a pan designed to be hung in the flue beneath said radiating devices.

6. In a device of the class described, a plurality of heat radiating members adapted to be hung in a flue opposite a pipe-opening therein and a pan designed to be hung in the flue beneath said members, said pan being curved as and for the purposes described.

In testimony whereof I have signed my name to this specification.

ANTHONY PETER DOELL.
